HOT AIR FURNACE

William S. Anderson, Jr., and George I. Staber,
Williamsport, Pa., assignors, by mesne assignments,
to Aviation Manufacturing Corporation,
a corporation of Delaware

Application August 9, 1937, Serial No. 158,104

3 Claims. (Cl. 126—107)

The invention relates to hot air furnaces.

One object of the invention is to provide a construction of hot air furnaces of the type in which the heater is provided with a magazine for solid fuel at one side and a combustion chamber with an arched roof at the other side, by providing a heater-body which is composed of longitudinal sections and transverse end sections secured together, and connected by expansion-joints.

Another object of the invention is to provide a hot air furnace with cast iron walls around the combustion chamber fire-box, which is adapted to avoid failure in, or grain growth of, the walls when cast of grey iron.

Another object of the invention is to provide a construction of hot air furnace of the magazine feed type which permits the walls of the fire-box and magazine to be formed of grey iron with the minimum number of sections or plates for economy in manufacture and efficient heating.

Another object of the invention is to provide the walls of the combustion-chamber with radiator-elements or pins whereby the heat will be radiated from the different portions of the walls approximately proportionate to the different temperatures produced therein by the fire, to avoid severe fluctuations in the metal walls, which contributes to grain growth or failure.

Another object of the invention is to provide a furnace of this type which is built up of a relatively few number of cast parts or sections and which are adapted to be sealed at the joints without machining or other expensive labor.

Another object of the invention is to provide an improved radiator for the products of combustion, which is adapted to be thoroughly and readily cleaned out when it becomes coated with soot, to avoid losses in heat transference to the surrounding air.

Other objects of the invention will appear from the detailed description.

The invention consists in the several novel features which are hereinafter set forth and are more particularly defined by claims at the conclusion hereof.

In the drawings: Fig. 1 is a perspective of a furnace embodying the invention, parts being broken away for illustrative purposes. Fig. 2 is a transverse section on line 2—2 of Fig. 3. Fig. 3 is a side elevation of the heater, the casing being shown in sections. Fig. 4 is a front elevation of the heater, separated from the jacket around the casing. Fig. 5 is a rear elevation of the heater. Fig. 6 is a section on line 6—6 of

Fig. 2. Fig. 7 is a horizontal section on line 7—7 of Fig. 3. Fig. 8 is a transverse section through the joint at the top of the dome or the apex of the arch over the fire-bed. Fig. 9 is a section of the sealing-joint between the rear wall 5 and the outer side-wall of the fuel-magazine, being a section on line 9—9 of Fig. 5. Fig. 10 is a transverse section on line 10—10 of Fig. 3. Fig. 11 is a horizontal section on line 11—11 of Fig. 5.

The invention is exemplified in a furnace comprising a heater surrounded by a sheet metal casing or jacket 29 which is provided with a cold-air inlet 21 and a top 23 having a hot air outlet 22 for connection to a duct for delivering the hot-air to its point or points of use.

The heater comprises a magazine *a* for coal at one side and adjacent the top of the heater-body; an inclined grate *b* of any suitable construction; an ash-pit *b'* below the grate, and a combustion-chamber *c* with an arched roof at the other side of the heater and above the grate, all extending longitudinally, and between the front and rear ends, of the heater-body. The walls of this heater are preferably cast of grey iron and of plate-like sections which are connected by sealed expansion-joints and provide a construction which is composed of a relatively small number of parts or castings for economy in manufacture and efficiency in operation. The heater-body comprises cast longitudinal sections *d*, *e*, *f*, 30 a front end or transverse section *g*, and a rear end or transverse section *h*. The longitudinal sections extend between the end or transverse sections. The front end-section or plate *g* is formed of a single casting and fits against the front ends of sections *d*, *e* and *f*. The rear-end section *h* is formed of a single casting and abuts against the rear ends of sections *d*, *e*, and *f*. The joints between the longitudinal sections and between the longitudinal and transverse sections 40 are of the expansion-type and provided with sealing means to permit the expansion and contraction of the sections without leakage of gases from the heater to the jacket. The section *d* comprises a portion *d'* which forms one side-wall 45 of the ash-pit, an inset portion *d*² provided with bearings 24 for the pivots of the grate-bars, an upwardly and inclined portion *d*³ which forms an inclined wall on which the fuel slides by gravity to the grate *b*, and a vertical upper portion *d*⁴, 50 which forms one side-wall of the magazine *a*. The section *e* has a lower portion *e'* which forms the other and low side of the ash-pit with bearings 25 for the grate-bars, and an outwardly and curved portion *e*³ which forms one side-wall 55.

of the combustion-chamber *c* from the grate to the peak of the arched roof. The section *f* comprises horizontal walls *f'* and *f²* which form the top and inner side of the magazine *a*, respectively, and a curved wall *f³* which extends upwardly from the lower end of wall *f²* and forms the other side of the arched roof of the combustion chamber. A continuation *26* depending from wall *f³* provides an opening between the magazine and the fire-bed to limit the delivery of fuel to the fire.

Front end-section *g* is provided with an integral forward extension *27* which extends through the front-wall of the jacket *20* and is provided with a door *28* for access to the ash-pit; an integral forward extension *29* which passes through the front wall of jacket *20* and is provided with a door *30* for access to the fire-bed and combustion-chamber *c*; a forward extension *31* which passes through the front wall of the jacket *20* and is provided with a door *32* for charging the magazine with fuel; and an integral upwardly extending duct *33* which forms a smoke-flue leading from the upper front corner of the combustion-chamber to a radiator *k* for the combustion products.

The longitudinal and transverse sections are held together by a series of longitudinal rods which are adapted to hold the sections *g* and *h* into abutting relation with the ends of the sections *d*, *e*, and *f*. The series of rods comprises: a pair of rods *35*, which extend loosely through lugs *36* which are integral with front-section *g*, lugs *37* which are integral with section *e*, and lugs *38* which are integral with section *h*; a rod *40* at the magazine side of the heater which extends through similar lugs on sections *g*, *d* and *h*; a rod *44* which extends loosely through lugs *45* on section *f*, lug *45^a* on section *g*, and a lug *45'* on section *h*; and a rod *41* which extends through section *g*, lugs *46* in the magazine *a* and integral with section *f*, and is screwed into section *h*. Each of the rods *35*, *40* and *44* is provided with nuts at its ends and rod *41* is provided with a nut at its front end. A spring *48* is interposed between each of the lugs *37* on the rear-end section *h* and a nut on each of said rods *35*, *40* and *44* to yielding force the longitudinal and transverse sections into abutting relation and to permit expansion and contraction thereof. A spring *48* is applied to the front end of rod *41* for the same purpose. Vertical ribs *e⁵* are formed on the outer side of section *e*. Flanges *d⁶* are formed on the ends of section *d* and have edges which conform to the adjacent edges of the sections *g* and *h*. This construction exemplifies a hot air furnace of the magazine-type which is built up of longitudinal and transverse or end-sections which are held together in abutting relation by tie rods and springs, so as to permit expansion and contraction of the section. The sections are held together without placing any load on the sealing foil hereinafter set forth.

Furnaces of different capacities can be produced by varying the length of the longitudinal sections.

To prevent leakage of gases from the combustion-chamber *c*, magazine *a*, or ash-pit, into the hot air chamber around the heater, it is necessary to seal the joints between the sections while permitting expansion or contraction thereof. This is accomplished by a strip of very thin metal-foil, e. g., .0020" aluminum-foil which is lapped around or over the walls of the joint and has its margins cemented by means of a fire-resistant cement, such as putty or furnace cement, to the

walls of the joint. The seal between sections *e*, *f*, at the apex of the arched roof of the combustion-chamber *c* is illustrated in Fig. 8. The arched walls *e³* and *f³* of sections *e* and *f*, respectively, rest on lugs *50* on the transverse sections. A strip of aluminum-foil *51* is lapped around the overlapping portions of said walls and has its margins sealed at *52* to walls *e³*, *f³*, respectively. The seal between the longitudinal sections and the transverse sections is illustrated in Fig. 9. A strip of aluminum-foil *54* lapped around the outer face and edge of the transverse end-wall and a bead *53* on the outer side of the longitudinal section has its margins bonded at *55* to said walls by cementitious material *55*. The seal between sections *d* and *f* is illustrated in Fig. 10 and comprises a strip of aluminum-foil *56* which laps the outer faces of said sections and has its margins cemented, as at *57*, to said walls, respectively. In practice, it has been found that a flexible strip, such as aluminum-foil, which has its margins cemented respectively to the joined walls, and is somewhat crinkled or loose between its margins, will form an effective seal for the joints which permits expansion and contraction of the sections responsively to thermal changes.

In the operation of the heater, different portions of the walls around the combustion-chamber, fire-bed and magazine are subjected to different temperatures. When the differential in temperature is high, due to constant fluctuation, growth fatigue of the grey iron in some portions of the walls results. The invention includes means for reducing and approximately equalizing the temperature of the different portions of the walls of the combustion-chamber to prevent growth fatigue.

It is important to prevent excessive localized temperatures in the different portions of the walls and to keep them below 950° F. This temperature reduction and equalization is accomplished by providing heat-radiating pins or elements *68* which are integrally formed with and on the outside of the walls of the combustion-chamber and in making them so they will have different heat-radiating or heat-transferring capacities in the different portions of the walls, approximately proportionate to the different temperatures therein. These different capacities may be attained by having longer elements *68'* in the zone of greatest temperature and shorter elements in the zone of lesser temperatures or by variation in the number of or in the distribution of the elements to provide the proportionate capacities desired.

For example, the section *e* which forms one side of the combustion chamber is provided with long pins *68'* which are gradually reduced in length, from the approximate point where the heat is greatest toward the ash pit where the heat is less and gradually reduced in length above the point of greatest heat, and again increased in length toward the apex of the combustion chamber where the temperature is high.

Pins *69* are also provided on the wall *f³* which forms the other side of the arched roof of the combustion-chamber, to reduce its temperature correspondingly to the other side. The inclined wall *d³* of section *d* on which the coal slides from the magazine to the fire-bed is provided with integral pins *70* to dissipate heat from the coal sufficiently to prevent the coal in the throat from releasing gases which will form coke and to retard the flow of heat from the fire-box to the coal in the magazine. The side and top

walls of the magazine are not provided with heat-radiating elements, so that their temperatures will not be reduced. The heat will be radiated from the hottest portions of the walls 5 more rapidly than from the cooler portions and, if the temperature differential is kept between 800° and 980° F., crystallization will be avoided. This feature also results in a more even and constant distribution of the heat from the heater, 10 as contradistinguished from the complete shutting down and firing of the furnace in relatively short cycles.

The radiator *k* comprises a pair of parallel longitudinal and horizontal tubular ducts *72*, *73* with 15 semi-circular front and rear connecting ends *74*, *75*. The rear ends of these branches terminate in an outlet *76* which is adapted to be connected to the smokestack or flue for carrying off spent products of combustion. The front end of the 20 radiator is provided with a pair of clean-out ducts *77*, respectively, aligned with the longitudinal ducts *72*. Each duct *77* is closed by a removable cover *78*. Heat transference through the walls and the efficiency of the radiator are reduced as soot accumulates on its inside. The 25 clean-out ducts *78* extend through the front-wall of the casing *20*. A clean-out duct for, and at the front of, each longitudinal branch of the radiator makes it possible to easily and thoroughly 30 clean both branches of the radiator and remove the soot, by a suitable tool.

The invention exemplifies a hot air furnace of the magazine-type; in which the walls of the heater are formed of longitudinal sections and 35 transverse or front and rear end-sections with sealed expansion-joints between the sections so they can be made of cast-iron and manufactured economically; in which means is provided for differentially radiating heat from the different 40 portions of the walls of the heater proportionately to their exposure to heat to keep the temperatures of the different portions approximately uniform and prevent grain growth or cracking of the grey iron; in which the radiator, 45 through which the products of combustion pass to the stack, is constructed of elongated branches and provided with means for facilitating its cleaning so that it will not be permitted to become partially filled with soot which reduces its efficiency; and which is efficient in operation.

The invention is not to be understood as restricted to the details set forth, since these may be modified within the scope of the appended claims, without departing from the spirit and 50 scope of the invention.

Having thus described the invention, what we

claim as new and desire to secure by Letters Patent is:

1. In a hot air furnace, the combination of a heater body comprising a longitudinally extending inclined grate at one side of the body, a longitudinally extending combined combustion chamber and fire-box disposed over the inclined grate, and a longitudinally extending fuel magazine at the upper side of the inclined grate for automatically delivering fuel to the grate, a casting surrounding, spaced from, and forming a hot air jacket around the top and sides of the combustion chamber and the magazine, the roof, one side wall, the roof and the end-walls of the combined combustion chamber and fire-box and the lower part of one side-wall of the magazine being provided with heat radiating elements having different heat transfer capacities approximately proportionate to the different temperatures generated respectively therein to maintain uniform 20 temperature in said walls.

2. In a hot air furnace, the combination of a heater body comprising a longitudinally extending inclined grate at one side of the body, a longitudinally extending combined combustion chamber and fire-box disposed over the inclined grate, and a longitudinally extending fuel magazine at the upper side of the inclined grate for automatically delivering fuel to the grate, a casting surrounding, spaced from, and forming a hot air jacket around the top and sides of the combustion chamber and the magazine, the roof, one side and both end-walls of the combustion chamber, and the lower part of one side-wall and the end-walls of the magazine being provided with heat radiating elements having different heat transfer capacities approximately proportionate to the different temperatures generated respectively therein to maintain uniform heat in said walls.

3. In a hot air furnace, the combination of an inclined grate, a hot air jacket, a heater body within said jacket and having at one side a longitudinally extending magazine with an inclined side leading to the grate for feeding fuel to the grate and at its other side a longitudinally extending combustion chamber with an arched roof, the body comprising metal longitudinal sides and top sections and transverse end sections forming the walls of the magazine and the combustion chamber, the walls of the combustion chamber being provided with heat-radiating elements, the inclined side of the magazine leading to the grate being provided with heat-radiating elements.

WILLIAM S. ANDERSON, JR. 55
GEORGE I. STABER.
